UNITED STATES PATENT OFFICE.

HART F. LANDON, OF MILWAUKEE, WISCONSIN.

AUTOMOBILE-HEADLIGHT.

1,401,613.

Specification of Letters Patent. Patented Dec. 27, 1921.

Application filed August 9, 1920. Serial No. 402,157.

To all whom it may concern:

Be it known that I, HART F. LANDON, a citizen of the United States, and resident of Milwaukee, in the county of Milwaukee, and State of Wisconsin, have invented certain new and useful Improvements in Automobile-Headlights; and I do hereby declare that the following is a full, clear, and exact description thereof.

10 My invention relates broadly to new and useful improvements in automobile and other vehicle head lights, and pertains particularly to attachments for diffusing the light rays whereby to prevent the annoyance which at present results from blinding and dazzling head lights.

15 It is the principal object of this invention to provide a simply constructed attachment which can be quickly and easily applied to 20 practically any type of vehicle head light.

An additional object is to provide an article of this nature which can be struck or stamped from sheet metal and quickly bent into proper shape.

25 Still another object of the invention is to provide a combined hood and light retarding means which will cut off or reflect downwardly the light rays which are usually projected upwardly from head lights as at present constructed.

30 With these general objects in view, the invention resides in the novel features of construction, combination and arrangement of parts which will be hereinafter more particularly described and claimed.

35 In the accompanying drawings:

Figure 1 represents a vertical sectional view taken on the plane of the line 1—1 of Fig. 2.

40 Fig. 2 is a front elevational view of a head light having my improved attachment applied thereto, and

45 Fig. 3 is a plan view of the attachment as it appears just after having been struck from a suitable blank.

Referring more particularly to the drawings, it will be seen that my invention is embodied in a head light of usual design including a casing 1, a reflector 2 of the 50 usual cup-shaped type having in its inner portion an incandescent lamp 3, a lens 4, and a lens retaining and assembling member 5. The casing 1 may be supported upon a suitable standard 6, or any other preferred 55 manner; likewise the current for the lamp

3 may be supplied as desired, for instance through the conductor wire 7.

The invention proper comprises a hood 8 and a light retarder 9; the former of which is disposed on the outside of the lens 4, 60 whereas the retarder is on the inside thereof and within the cup-shaped reflector 2. Inasmuch as the rays of light which are projected through the lower half of the lens 4 do not dazzle approaching pedestrians, or 65 the drivers of approaching vehicles, to any extent, this portion of a head light is usually left unobscured, consequently in the present instance both the hood 8 and the retarder 9 are disposed to shield the upper 70 half of the lens 4 and to diffuse the light rays which normally project through such portion of the lens.

The hood 8 in plan view, or before being shaped, is substantially in the form of a 75 semi-circle as shown in Fig. 3, but when bent in the necessary manner, its intermediate portion is located somewhat above the center of the lens as indicated at 10 in Fig. 2, whereas the end portions thereof extend 80 below the center as at 11. The arcuate edge of the blank from which the hood is formed is bent laterally as at 12 to form an attaching flange which, when the device is in place on the head light is clamped between the retaining member 5 and the lens 4 (see Fig. 1). Further and more positive attachment 85 of the end portions 11 is procured as a result of the provision of attaching fingers 13, the same being bent around the edge of 90 the lens to embrace the inner and outer faces thereof.

The light retarder 9 consists of a semi-circular frame 14 having a plurality, in the present instance three, light retarding plates 95 15 which are disposed parallel and horizontally. In practice the frame 14 and plates 15 are stamped from a semi-circular blank in such a manner that said plates are attached to the frame at their lower opposite corner, such means of connection being clearly indicated at 16 in Fig. 3. At each opposite corner of the frame 14 is a lateral and diametrically extending spacing and attaching leg 17. The hood 8 and the frame 105 14 are joined in the center of their arcuate edges by a connecting strap 18, thus retaining the two parts of the attachment together and permitting ready assembly thereof.

When in use the hood 8 is applied as here- 110

inbefore set forth, whereas the connecting strap 18 is bent into substantially U-shape to engage the edge of the lens 4, thus disposing the frame 14 and the parts carried thereon by on the inside of said lens. As indicated in Fig. 1 the frame is positioned diagonally with respect to the vertical plane of the lens and has its lower end spaced therefrom by the legs 17. In view of the fact that the material from which this attachment is formed is of light gage sheet metal, these legs 17 as well as the attaching fingers 13 can be readily bent about the edge of the lens, and consequently as a result the lower edge of the frame 14 can be spaced different distances away from the vertical plane extending through its upper edge. The retarder plates are bent inwardly in parallelism and as shown they preferably define an acute angle with said frame so that although they retard direct rays from the light 3, downwardly deflected rays from the upper portion of the reflector 2 may pass therebetween.

From the foregoing description taken in connection with the accompanying drawings, it will be seen that I have devised a very simply constructed light diffusing means which can be inexpensively formed of light gage sheet metal and quickly and easily applied to standard types of head lights. However, should it be necessary, various changes may be made in the form and proportions of the different parts of the attachment to accommodate it for use in connection with unusual types of head lights, without departing from the principles of the invention or sacrificing any of the advantages.

Some of the rays which are projected forwardly from the lamp or from the reflector near its center will pass under or between the

plates 15 either in a horizontal direction or inclined slightly upwardly. These for the most part will be deflected by the hood 8.

I claim:

1. The combination of a headlight attachment comprising a one-piece hood, and light retarder bent to be disposed on opposite sides of a headlight lens, the light retarder including a frame and a plurality of light reflecting plates extending transversely across the frame in forwardly and downwardly disposed planes.

2. The combination of a headlight attachment comprising a one-piece hood and light retarder bent to be disposed on opposite sides of a headlight lens, the light retarder including a downwardly and rearwardly extending frame and a plurality of light reflecting plates extending transversely across the frame in forwardly and downwardly inclined planes, each plate being in rear of and below the preceding plate, and means for adjustably connecting the lower end of said frame to the side edges of the lens to vary the angles of said plates.

3. In combination, a headlight including a lens, a hood projecting forwardly from the upper portion of the headlight outside of the lens, a light reflecting member disposed within the headlight casing on the inside of said lens and extending downwardly and rearwardly from the upper edge thereof, and a connecting strip joining the hood and light reflecting member and bent over the edge of the lens to aid in attaching the same thereto.

In testimony that I claim the foregoing I have hereunto set my hand at Milwaukee in the county of Milwaukee and State of Wisconsin.

HART F. LANDON.
